GLAND ADJUSTING MECHANISM

Samuel G. Green, Gray, Ga.

Application December 18, 1936, Serial No. 116,551

1 Claim. (Cl. 89—14)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a gland adjusting mechanism.

In a water cooled machine gun having a recoiling barrel it is necessary to provide packing for the movable joints in order to prevent leakage of the cooling medium which is contained in a jacket surrounding the barrel. In the Browning type of machine gun the packing for the breech end of the barrel is held in place by a gland that can only be adjusted after removing the water jacket.

10 The purpose of this invention is to arrange the barrel mounting so that the gland which is positioned internally of the assembly may be adjusted from an external position.

15 A further object is to provide a simple and efficient means for locking the gland in adjusted position.

To these and other ends, the invention consists in the construction, arrangement and combination of elements described hereinafter and pointed out in the claim forming a part of this specification.

A practical embodiment of the invention is illustrated in the accompanying drawing, wherein:

20 Fig. 1 is a longitudinal sectional view of a portion of a machine gun showing the gland and gland locking means.

Fig. 2 is a view in elevation and partly in section of the gland.

25 Fig. 3 is a sectional view on the line 3—3 of Fig. 1.

Fig. 4 is a longitudinal sectional view of a modified form of the invention; and

30 Fig. 5 is a sectional view on the line 5—5 of Fig. 4.

The machine gun illustrated in the drawing is of the Browning type and comprises a receiver 5 having in its front end a trunnion block 6 formed with a passage 7 for receiving a gun barrel whose breech end is slidably supported in the bearing portion 9 of the block. This arrangement is similar to a cylinder and piston construction.

35 The passage forwardly of the bearing portion 9 is enlarged and spaced from the barrel and forms an annular shoulder 10 for seating a ring

11. A packing 12 is held against the ring 11 by an elongated gland 13 which is inserted into the passage from the front end of the trunnion block and is threaded to a tubular extension 14 of the block. When the gun is completely assembled the front end of the gland is disposed within a jacket 15 which is threaded on the extension 14 and contains a fluid for cooling the gun barrel.

An annular row of teeth 16 is formed on the outer surface of the gland adjacent its rear end 10 and when the gland is threaded in the block to confine the packing 12, the teeth are generally in line with an aperture 17 in the under side of the block. This aperture leads into a longitudinally extending slot 18 in the under side of 16 the block. A spring detent 19 carried by the block extends through the aperture 17 and engages the teeth on the gland to lock the gland in position of adjustment.

When it is desired to rotate the gland to vary the compression of the packing the detent 19 is moved out of locking engagement with the teeth, and a tool, such as a screw driver, is inserted through the aperture, brought into engagement with the teeth, and then moved tangentially of 25 the gland to impart rotational movement to the gland and regulate the compression of the packing 12.

In the modification shown in Fig. 4 the gear teeth 20 on the gland 21 are engaged by a pinion 22 which is mounted on a shaft or pin 23 carried by the trunnion block 24. The pinion is held against rotation by a spring detent 25 similar to that shown in Fig. 1.

I claim:

In a gun, a receiver having a bearing, a jacket for a cooling liquid on the front of the receiver, a gun barrel slidably supported in the bearing of the receiver and extending forwardly through the jacket, a packing between the barrel and receiver and positioned forwardly of the bearing to establish a liquid seal, a gland threaded in the receiver to establish a liquid seal and extending rearwardly to confine the packing, teeth on the outer side of the gland adjacent its rear end, and said receiver formed with an aperture giving access to the teeth of the gland from the exterior of the receiver.
